UNITED STATES PATENT OFFICE.

CHARLES WARD, OF CHARLESTON, WEST VIRGINIA.

WATER-TUBE BOILER.

1,020,234.

Specification of Letters Patent. Patented Mar. 12, 1912.

Application filed July 19, 1910, Serial No. 572,684. Renewed December 27, 1911. Serial No. 688,098.

To all whom it may concern:

Be it known that I, CHARLES WARD, citizen of the United States, residing at Charleston, in the county of Kanawha and State of West Virginia, have invented certain new and useful Improvements in Water-Tube Boilers, of which the following is a specification.

This invention relates to water-tube boilers, and its object is the production of a steam generator having parts of special construction, which parts, together with devices for increasing the circulation, are arranged in a particular manner believed to materially advance the economy and efficiency of the boiler.

The construction and arrangement of the various features comprising this invention are illustrated in the accompanying drawings, of which—

Figure 1 represents a vertical and longitudinal section showing all parts assembled. Fig. 2 is an end view of one of the closures of the circulating or main tube, and a part cross-section of that tube.

The same letter is used to refer to the same part throughout the description and drawings.

The drum A located at the highest point of the structure, is connected with the header B, that is termed in this description the upper header. The upper header is connected with the lower header C by the tubes D which are customarily inclined from rear to front as illustrated.

Extending through the two headers, preferably, through the lower portions of the headers, and having usually the same inclination as tubes D, is the main circulating tube E, having the end closures or heads F and G ordinarily of the bell-shaped formation shown. Portions of the main tube E near the closures are provided with slots e opening into the headers B and C. The feed water pipe H enters the main circulating pipe E centrally through the closure F. The shaft J enters the main circulating tube E centrally through the closure G, by way of the thrust bearing j, and stuffing box K. Within the tube E the shaft J has secured to it a propeller wheel L.

The operation of this invention may be described as follows: The normal, unaided circulation takes the general direction through the main tube indicated by the arrows, and through the tubes D toward the

upper header B. The reason for the circulation stated is that the body of water in the main tube is much larger than that contained in any single small tube, and the central portion of the water in the main tube is less heated in the same time than the water in the small tubes, with the result that the water in the main tube is relatively heavier, bulk for bulk, and descends accordingly. It will be observed that the feed water entering through the nozzle of the pipe H, usually with considerable velocity, also takes the direction of circulation, and, I provide within the tube E the cones h 60 and h' in the path of the feed water jet. The resulting action of the feed water jet upon the surrounding water is to increase the velocity of its movement in the direction of circulation, after the manner of a jet 65 pump or injector.

It is believed to be now clear that the velocity of the circulating water may be increased by suitably revolving the propeller L. The feed water jet and the propeller 70 both impel the water in tube E in the same direction and at the same time when so desired.

The elevated drum A affords ample space for the separation and retention of the 75 steam.

Having now described this invention, and explained the mode of its operation, what I claim is:—

1. In a boiler, the combination with headers, of a main circulating tube passing through the headers and having openings in communication with the headers near the ends of said tube, a shaft arranged to enter one end of the said main tube, and a 90 wheel secured upon the shaft constructed and arranged to impel the water through the openings in said tube at the same end.

2. In a boiler, the combination with headers, of a main circulating tube passing 100 through the headers and having openings near the ends in communication with the headers, a shaft arranged to enter one end of said main tube, and a propeller wheel upon the shaft arranged to impel the water 105 through the said main tube.

3. In a boiler, the combination with headers, of a main circulating tube connecting the headers and having openings near the ends in communication with the headers, 110 a shaft arranged to enter one end of said main tube, a propeller wheel secured to the

shaft and arranged to impel the water through the said main tube, and a feed water pipe passing through the other end of said main tube.

5. 4. In a boiler, the combination with upper and lower headers, of an inclined main circulating tube passing through the headers and having openings near the ends in communication with the headers, a shaft arranged to enter one end of said main tube, and a wheel secured upon the shaft constructed and arranged to impel the water through the openings in said main tube at the same end.

15. 5. In a boiler, the combination with upper and lower headers, of an inclined main circulating tube passing through the headers and having openings near the ends in communication with the headers, a shaft arranged to enter one end of said main tube, and a propeller wheel upon the shaft arranged to impel the water through the said main tube.

6. In a boiler, the combination with upper and lower headers, of an inclined main circulating tube connecting the headers and in communication with the headers, a shaft arranged to enter one end of said main tube, a propeller wheel secured to the shaft and arranged to impel water through said main tube, and a feed water pipe passing through the other end of said main tube.

7. In a boiler, the combination with headers, of a main circulating tube connecting the headers and in communication with the headers, a feed water pipe arranged to enter one end of the main tube, and cones arranged in the path of the feed water whereby the surrounding water is actuated in the direction of circulation.

40. 8. In a boiler, the combination with upper and lower headers, of an inclined main circulating tube connecting the headers and in communication with the headers, a feed

water pipe arranged to enter the higher end of the said main tube, and means located in another portion of said main tube for increasing the velocity of the water in the tube in the direction of the entering feed water.

50. 9. In a boiler, the combination with two headers one arranged higher than the other, of a series of inclined tubes connecting the said headers, a relatively larger main circulating tube arranged below the said inclined tubes and extending in the same direction, the said circulating tube connecting the lower parts of the said headers immediately below the said tubes and having an inclined position, and water-actuating devices located within the said main circulating tube.

55. 10. In a boiler, the combination with headers, of a main circulating tube connecting the headers and in communication with the headers; a feed water pipe arranged to enter one end of the main tube, cones arranged in the path of the feed water whereby the surrounding water is actuated in the direction of circulation, and water-actuating devices located within said main tube at a distance from the entrance of said feed pipe for aiding the circulation.

60. 11. In a boiler, the combination with upper and lower headers, of an inclined main circulating tube connecting the headers and in communication with the headers, a feed water pipe arranged to enter the higher end of said main tube, and cones arranged in the path of the feed water whereby the surrounding water is actuated in the direction of circulation.

65. In testimony whereof I affix my signature in presence of two witnesses.

CHARLES WARD.
